UNITED STATES PATENT OFFICE.

VERNON F. PRENTICE, OF WORCESTER, MASSACHUSETTS.

RADIAL DRILLING-MACHINE.

SPECIFICATION forming part of Letters Patent No. 661,586, dated November 18, 1900.

Application filed August 11, 1896. Serial No. 602,381. (No model.)

To all whom it may concern:

Be it known that I, VERNON F. PRENTICE, a citizen of the United States, residing at Worcester, in the county of Worcester and 5 State of Massachusetts, have invented a new and useful Improvement in Radial Drilling-Machines, of which the following is a specification, accompanied by drawings forming a part of the same, in which—

10 Figure 1 represents a side elevation of a drilling-machine embodying my invention. Fig. 2 is a plan view. Fig. 3 is a horizontal sectional view on line 3 3, Fig. 1; and Fig. 4 is a front view of the rotating head in which 15 the spindle is supported.

Similar numerals refer to similar parts in the different figures.

The object of my present invention is to provide a radial drilling-machine in which 20 the cutting-tool shall be capable of four independent adjustments—viz., first, an adjustment around a vertical axis; second, a sliding adjustment in a vertical plane; third, a sliding adjustment in a horizontal plane, and, 25 fourth, an adjustment around a horizontal axis; and I attain this object by means of the construction and arrangement of parts, as hereinafter described.

Referring to the accompanying drawings, 30 1 denotes a vertical post supported upon a suitable base or bed plate 2. Upon the post 1 is mounted a rotating sleeve 3, capable of turning upon a vertical post and provided with ways 4 4, upon which is a carriage 5, capable of a vertically-sliding movement on said ways by means of connected actuating mechanism, as hereinafter described. The carriage 5 is provided with horizontal ways 6, which support the radial arm 7, upon the 35 outer end of which is mounted a head 8, capable of rotating about a horizontal axis and supporting the rotating drill-spindle 9 and connected feeding mechanism, as hereinafter described.

40 Journalized within the post 1 and concentrically with the rotating sleeve 3 is a vertical shaft 10, driven near its lower end by a pair of beveled gears 11 and 12 from a horizontal counter-shaft 13, which is provided 45 with the usual step-pulley 14 and back gearing 15. To the upper end of the upright central shaft 10 I attach a gear 16, engaging a

spur-gear 17 on a vertical shaft 18, journaled in bearings upon the outside of the rotating sleeve 3 and having a spline connection with 55 a beveled gear 19, supported by the sliding carriage 5. The beveled gear 19 engages a beveled gear 20 on a short intermediate shaft 21, journaled in the vertically-sliding carriage 5. The intermediate shaft 21 carries a 60 spur-gear 22, engaging a spur-gear 23, which is provided with a long hub 24, journaled in the carriage 5 and having a spline connection with a horizontal shaft 25, which is journaled in the radial arm 7. 65

The outer end of the horizontal shaft 25 carries a beveled pinion 26, which engages a beveled gear 27, having a spline connection with the drill-spindle 9, journaled in the head 8, whereby the rotary motion of the counter-shaft 13 is communicated to the drill-spindle. Turning upon a stud 28, supported by the framework forming the head 8, is a cone-pulley 29, having an attached beveled gear 30, which is driven by the beveled gear 27. 70

The cone-pulley 29 has a belt connection with a cone-pulley 31, attached to a short horizontal shaft, which carries a pinion 32, engaging a beveled gear 33 on an upright shaft 34. The shaft 34 carries a beveled pinion 35 80 at its lower end, engaging a beveled gear 36 on a horizontal shaft 37, which extends back of the drill-spindle 28 and carries a worm 38, engaging a worm-wheel 39 on a vertical shaft 40, having at its upper end a spur-gear 41, 85 which is in mesh with a gear 42, attached to a rotating nut 43, journaled in the head 8 and held from longitudinal movement. The nut 43 engages the feed-screw 44, having a swivel connection in the usual manner with the 90 drill-spindle 28, so that the rotary motion of the drill-spindle will communicate a feeding motion to the screw 44 and connected drill-spindle through the intermediate mechanism above described. 95

Upon the outer end of the radial arm 7, and preferably integral therewith, is a circular worm-wheel 45, concentric with the shaft 25, journaled in the radial arm 7. A worm 46, journaled in and carried by the head 8, engages the teeth of the worm-wheel 45 and is provided with an angular shank to receive a wrench by which the worm 46 is rotated, causing the head 8 to be rotated around the 100

worm-wheel 45. The head 8 is held against the stationary worm-wheel 45 by means of bolts, whose heads are held in a circular T-shaped slot 48, concentric with the axis of the shaft 25.

A horizontal sliding motion is given to the radial arm 7 by means of a screw 49, journaled at one end in a bearing 50, attached to the radial arm and held from longitudinal movement in said bearing, and having its opposite and screw-threaded end engaging a nut 51, held by a bracket 52, attached to the vertically-sliding carriage 5. The screw 49 is actuated by miter-gears 53 and a spindle 54, having a shank 55 to receive a wrench.

The sliding carriage 5 is moved vertically on the ways 44 by means of a screw 56, engaging a nut 57, attached to the carriage. The screw 56 is journaled in and held from longitudinal movement by a bearing 58, attached to the rotating sleeve 3. The upper end of the screw 56 carries a spur-gear 59 in mesh with a pinion 60, rotating upon a stud held in a vibrating lever 61, which is pivoted concentrically with the screw 56. The vibrating lever 61 also carries a pinion 62, rotating upon a stud held in the lever similar to and in engagement with the pinion 60, but not in engagement with gear 59, which is attached to the screw 56. By vibrating the lever 61 one of the pinions 60 or 62 is carried into engagement with the pinion 63, attached to the rotating shaft 18; but when the lever 61 is held in a central position both pinions 60 and 62 are held out of engagement with the driving-pinion 63. When the pinion 60 is carried into engagement with the pinion 63, the screw 56 will be rotated in one direction by the driving-pinion 63 through the intermediate pinion 60; but when the pinion 62 is carried into engagement with the pinion 63 the screw 56 will be rotated in the opposite direction through the intermediate pinions 62 and 60.

The vibrating lever 61 is moved into either of the three positions named above by means of a vertical shaft 64, journaled in bearings at the side of the rotating sleeve 3 and carrying at its upper end a radial arm 65, connected by a link 66 with the outer end of the lever 61. The shaft 64 is rocked by means of a handle 67, attached to the shaft and carrying a spring-actuated latch 68, engaging one of a series of three holes arranged in a fixed plate 69, concentric with the axis of the rocking shaft 64, thereby locking the shaft in position. The head 8 is provided with a projecting handle 70, which enables the attendant to rotate the sleeve 3 and swing the radial arm around the axis of the vertical shaft 10.

For ordinary purposes the sleeve 3 is left free to be rotated on the post 1 by means of the handle 70; but when required the sleeve

is clamped upon the post by means of one or more clamping-bolts, one of which is shown at 71, having a head 72 at one end and a nut 73 at the opposite end and extending through the sleeves 74 and 75, held in the rotating sleeve 3 and are concave on one side, as at 76, to fit the convex side of the post 1. A small space 77 is left between the inner ends of the sleeves to allow them to be drawn together and clamped against the post, thereby tightening the rotatable sleeve 3.

What I claim as my invention, and desire to secure by Letters Patent, is—

1. In a radial drilling-machine the combination of a supporting-post, a sleeve held on said post and capable of rotation about a vertical axis and provided with vertical ways, a carriage capable of sliding on said ways, said carriage having horizontal ways, a radial arm capable of sliding in said horizontal ways, a head supported by the end of said radial arm and capable of rotating about a horizontal axis, and a rotating drill-spindle journaled in said head, substantially as described.

2. In a radial drilling-machine, the combination of a supporting-post, a rotatable sleeve journaled on said post and provided with vertical ways, a carriage capable of sliding on said ways, said carriage having horizontal ways, an arm capable of sliding on said horizontal ways, a head carried by said arm and capable of rotating about a horizontal axis and a rotating drill-spindle carried by said arm and with the axis of said drill-spindle in a plane at an angle with the horizontal axis of its rotating head, substantially as described.

3. In a radial drilling-machine, the combination of a vertical post, a sleeve rotatable on said post, a carriage capable of a vertical movement on said sleeve, a radial arm held by said carriage and capable of a radial movement thereon, a head supported by the end of said arm and capable of rotating in a plane at right angles to the radial movement of said arm, and a drill-spindle journaled in said head, substantially as described.

4. In a radial drilling-machine, the combination of a vertical post, a radial arm held by said post, a shaft journaled concentrically in said post, a vertical shaft outside said post and connected with said concentric shaft, a horizontal shaft journaled in said radial arm and a short intermediate shaft between said vertical and said horizontal shafts and gears carried by said intermediate shaft by which said vertical and said horizontal shafts are connected, substantially as described.

Dated this 8th day of August, 1896.

VERNON F. PRENTICE.
